DESIGN FOR A TEXTILE FABRIC

Robert Buzzini, Springdale, Conn., assignor to Frank Associates, Inc., New York, N. Y., a corporation of New York

Application January 7, 1941, Serial No. 97,849

Term of patent 3½ years

To all whom it may concern:

Be it known that I, Robert Buzzini, a citizen of the United States residing at Springdale, Conn., in the county of Fairfield and State of Connecticut, have invented a new, original, and ornamental Design for a Textile Fabric, of which the following is a specification, reference being had to the accompanying drawing, forming part thereof,

The drawing shows a plan view of a textile fabric illustrating my new design.

I claim:

The ornamental design for a textile fabric,
as shown.

ROBERT BUZZINI.
